2 Claims. (Cl. 100—52)

The invention relates to a press comprising a supporting member for the support of the article to be pressed and a straight guiding device fixedly connected to the supporting member which with the aid of an actuating mechanism connected hereto and active under influence of a pressure medium is movable along the guiding device to and away from supporting member.

With such a press, often equipped with a hydraulic actuating mechanism, the cylinder of the mechanism is usually fixedly attached to a pressure member or yoke connected to the guiding device, while the piston of the mechanism is attached to the movable pressure member or die, which is guided between a heavy frame construction comprising the first mentioned pressure member or yoke, the supporting piece or anvil and a pair of parallel columns.

The length of the stroke of the movable pressure member is, of course, determined by the length of the cylinder. When a great stroke length is required, e.g. with a cheese press where the article to be pressed consists of a number of separate units placed on each other, more the number of the units should be variable, consequently a considerable length of the cylinder is required which makes the press more valuable but is also a disadvantage due to the space required by the press even with a horizontal arrangement of the guiding device. In other words, the height or length of the press could be twice the length of the piston stroke due to the height of the article to be pressed in its unpressed condition.

The invention aims at providing a press which operates over a great length and yet is actuated by a press cylinder with a short stroke so that the press is inexpensive and has few disadvantages due to its small dimensions. Therefore, a press of the type described in the preamble and made in accordance with the present invention contemplates using a second pressure member at the side of the first pressure member facing away from the supporting piece and which is movable along the guiding device. In addition, an actuating mechanism is provided for the movement of the second pressure member and is connected to said second pressure member with both pressure members alternately attachable and releasable respectively with regard to the guiding device.

On hydraulically or pneumatically operating the actuating mechanism, which may comprise a cylinder with a movable piston therein with the press according to the invention, since the pressure pieces are alternately attachable to the guiding device and releasable therefrom, when the second pressure piece which is most remote from the supporting piece has first been attached to the guiding device and then the first pressure piece has been released from the guiding device, this first pressure piece will move to the supporting piece by expansion of the actuating mechanism, on compressing the article about a distance, equal to the expansion movement of said mechanism, after which, after attaching of the first pressure piece to the guiding device and then releasing of the second pressure piece from the guiding device, the second pressure piece e.g. by contraction of the actuating mechanism or e.g. by action of gravity, the operation of an elastic member or otherwise, will move about the distance of the

2

contraction in the direction of the supporting piece, so that the original condition has been obtained, in which the pressure pieces, however, have been shifted about a distance equal to the expansion and contraction movement respectively, along the guiding device, after which the cycle may be repeated.

With an embodiment of the press according to the invention, having an actuating mechanism comprising a cylinder and a piston movable therein, whereas the cylinder space can be brought in communication with a source for a pressure medium, according to the invention the cylinder is attached to the one pressure piece and the piston to the other pressure piece.

Preferably with a press, the guiding device of which having one or more columns, according to the invention the pressure pieces are provided with an inner deformable sleeve of flexible material embracing the column and an outer non-deformable sleeve of hard material surrounding the inner sleeve at some radial distance, which sleeves at both ends are sealingly connected to each other and the outer sleeve is attached to the pressure piece, whereas the annular space between the sleeves can be brought in communication with the source of the pressure medium, via a duct.

With an embodiment of the press according to the invention one of the pressure pieces is provided with a valve mechanism incorporated in the pressure duct system and the other pressure piece with an actuating rod having stops, for cooperating with an actuating member of the

20 valve mechanism, a tension-spring being arranged between both pressure pieces, one and another such that in one position of the actuating member of the valve mechanism, for moving the first pressure piece against the spring action to the supporting piece, pressure medium is supplied to the cylinder, as well as to the annular space between the sleeves at the second pressure piece and then pressure medium is discharged from the annular space between the sleeves to the first pressure piece and at the end of the piston stroke, the actuating member of the

25 valve is brought into a second position by cooperation with the actuating rod, in which position pressure medium is supplied to the annular space between the sleeves at the first pressure piece and then pressure medium is discharged from the cylinder as well as from the annular

30 space between the sleeves at the second pressure piece, whereas a reversing valve is present in the pressure duct system, by means of which, for moving the first pressure piece away from the supporting piece, the communication of the pressure medium source with the sleeves at one

35 pressure piece and with the cylinder and the sleeves at the other pressure piece respectively, is reversible.

The invention will become more apparent from the following detailed description taken in conjunction with the accompanying drawings in which:

55 FIG. 1 is a diagrammatical view of the press;
FIG. 2 is a schematic presentation of the circuitry of the hydraulic pressure system; and

FIG. 3 is a cross-section of a pressure chamber illustrating the manner by which the sleeve grips a column.

60 The press shown is of the usual vertical arrangement and of the hydraulic type, with a transverse supporting member for the support of an article to be pressed, a pair of vertical columns 2 attached to the support member, which columns at their upper ends are joined by a

65 bridge member 3 to constitute a fixed frame and a first transverse pressure member 4, movable up and down between the columns, to which member 4 the piston rod 5 of an actuating mechanism is attached.

70 A cylinder 6 of the actuating mechanism has a rather small axial dimension and is attached to a second transverse pressure member 7, which is also guided up and

down along the columns. A piston 8 attached to the piston rod has consequently a short length of stroke. The pressure members 4, 7 have each been provided at their ends with a sleeve-like gripping means embracing the column 2, said means comprising an inner, easily deformable sleeve 9 (e.g., of rubber) resting against the column, and coaxially there around a rigid sleeve 10 (e.g., from metal) which is attached at both ends sealingly to the rubber sleeve, leaving free a pressure chamber. Furthermore, the metal sleeve is attached in a bore of the pressure member. If a pressure medium (e.g., a liquid under pressure) is admitted into the pressure chamber C between the sleeves 9, 10, the rubber sleeve 9 is tightly pressed against the column 2 so that the first pressure member 4 is attached to the column. As soon as the pressure medium is discharged from the pressure chamber C between sleeves 9, 10 the pressure member 4 is released from the columns and then can be shifted again.

A reservoir, not shown, for the pressure liquid is via pipes, not shown, in communication with the cylinder space above and below the piston thereof as well as with the pressure chamber C between the sleeves 9, 10 of the gripping means.

By now admitting the pressure medium to the gripping means of the second pressure member 7 and also to the upper side of the cylinder 6 attached to the said pressure member while the pressure medium of the gripping means of the first pressure member 4 is discharged, the pressure member 4 will move downwards against the action of tension springs 14, attached with their ends to the pressure members 4 and 7. Due to the counter-pressure by an article to be pressed, member 4 will exert thereon a pressure which amounts to the pressure of the pressure medium multiplied by the surface of the piston in the cylinder. This only takes place if the clamping action on the columns 2 of the inner sleeves 9 of the gripping means of the pressure member 7 is great enough to take up the axial pressure exerted by the cylinder. If that would not be the case, the pressure member 7 would then slide upwards along the columns.

The axial force which the gripping means of pressure member 4 or 7 can take up equals the normal force with which the inner sleeves 9 are pressed against the columns, multiplied with the coefficient of friction between inner sleeve and column. The normal force with which an inner sleeve is pressed against the column is approximately equal to the surface of the cylinder multiplied by the pressure of the pressure medium. The press will operate well if the surface of the cylinder 6 is smaller or at most equal to the total surface over which the inner sleeves 9 of the gripping means are pressed against the columns 2 multiplied by the coefficient of friction between inner sleeve and column.

As soon as the pressure member 4 has nearly come to the end of the shift, determined by the piston stroke length, with the aid of an operating rod 11, attached to the pressure member 4 and having an upper and a lower stop, 11a and 11b respectively, a valve mechanism A comprising reversing valves 12 and 13 are in communication with pressure 7 and controlled by the stop 11a. This valve mechanism A provides a changing over in the circuit of the pressure medium such that at first the pressure medium is admitted to the gripping means of the first pressure member 4 and then the pressure medium is discharged from the gripping means of the second pressure member 7 as well as from the cylinder. As soon as, owing to this, the first pressure member 4 has been attached to the columns and the second pressure member 7 has been released from the columns, the second pressure member 7 will move downwards under influence of the gravity action and under the action of the tension springs 14. The downward movement of the second pressure member 7 will continue till the operating rod 11 again changes over the operation of the valve mechanism A via the stop 11b, by which the original connection of the

5 circuit of the pressure medium is restored. For this purpose first of all the pressure medium is again admitted to the gripping means of the second pressure member 7 and also to the upper side of the cylinder 6, thereafter the pressure medium is discharged from the gripping means of the first pressure member 4. If the assembly, constituted by the first and second pressure members and the cylinder with its piston, is located at the upper side of the columns 2, it will move downwards step-wise until it meets a counter-pressure as long as there is still a distance present between it and the article to be pressed. The stages are of course equal to the relatively short stroke of the piston 8 in the cylinder. When the compression which the article is experiencing is greater than the piston stroke, the assembly will simply move a step further downward at the end of the said stroke.

10 In order to complete the press action, a second reversing valve B, shown in the circuitry of the pressure medium (FIG. 2), can be actuated by hand so that on actuating a hand lever (not shown) of said second reversing valve from a first position for the above-described step-wise downward movement of the assembly to a second position, a changing over in the circuit will be contained such that the sequence of attaching the gripping means to the columns is reversed. Instead of the gripping means of the second pressure member 7 being clamped on the columns and the upper side of the cylinder 6 being supplied with pressure fluid, the gripping means of the first pressure member can be clamped on the said columns to coincide with the application of pressure on the lower side of the cylinder 6, and directly thereafter to have the release of the gripping means of the second pressure member 7 from the columns take place, will provide a step-wise upward movement of the press assembly.

15 20 25 30 35 40 45 When the press is only used for pressing articles which experience a permanent change of shape, the gripping means of the first pressure member will never need to take up an axial pressure. They will only have to be able to carry the weight of the second pressure member with everything attached thereto. In that case the surface with which the sleeve 9 of the gripping means of the first pressure member grips the column will be much smaller, or in other words, the sleeves 9 can be much shorter than the sleeves 9 of the gripping means of the second pressure member 7.

I claim:

1. A press comprising two columns held in fixed parallel relationship, a transverse supporting member permanently fixed to said columns for supporting an article to be pressed, a first transverse pressure member being slidably mounted on said columns, a second transverse pressure member being slidably mounted on said columns between said first pressure member and said supporting member, flexible sleeve-like gripping means mounted on each end of the pressure members and slidably receiving the press columns therein, tension spring means being positioned between the pressure members and having the ends thereof connected to the pressure members, said spring means biasing said pressure members toward each other, a pressure cylinder mounted on said first pressure member, a piston reciprocably mounted within said cylinder, a piston rod having one end connected to said piston and the other end thereof connected to said second pressure member, said gripping means each comprising a flexible inner sleeve and a rigid outer sleeve, the inner and outer sleeves being sealingly connected to each other and having a space therebetween for forming a pressure chamber, an inlet for introducing a pressure fluid to each of said pressure chambers, said inlet also serving as an outlet for exhausting the pressure fluid, reversing valve means for supplying and exhausting pressure fluid to the inlet of the pressure chambers and to the pressure cylinder, and means carried by said second pressure member to operate the reversing valve, said gripping means serving to adjustably 50 55 60 65 70 75 position said pressure members along said columns, the

reversing valve means serving to introduce fluid pressure to the gripping means of said first pressure member and to the cylinder and to exhaust fluid pressure from the gripping means of said second pressure member whereby the second pressure member is moved by said piston rod towards said supporting member against the action of said spring means while said first pressure member is held in engagement with said columns until said piston rod reaches a predetermined point and then a change over takes place in the pressure fluid circuit whereby the second pressure member is clamped to said columns by said gripping members and said first pressure member is unclamped from said columns and allowed to be pulled towards said second pressure member by the action of said spring means.

2. A press according to claim 1 in which said reversing valve means includes a first valve mounted on said first pressure member, an actuating rod mounted on said second pressure member, a duct system through which the fluid pressure flows, and a second, manually operated, valve, the second valve being adapted to control the direc-

tion of movement of the pressure members as a unit either towards or away from said supporting member, said actuating rod having first and second stops for engaging and operating said first valve.
